UNITED STATES PATENT OFFICE.

FREDERICK W. GOLDSTONE, OF BURKS FALLS, ONTARIO, CANADA.

DOOR-LOCK.

No. 909,888.

Specification of Letters Patent.

Patented Jan. 19, 1909.

Application filed April 24, 1908. Serial No. 429,030.

To all whom it may concern:

Be it known that I, FREDERICK W. GOLDSTONE, subject of the King of Great Britain, residing at Burks Falls, in the Province of 5 Ontario, Canada, have invented certain new and useful Improvements in Door-Locks, of which the following is a specification.

The present invention relates to certain new and useful improvements in latches of 10 that type which are commonly employed upon doors and other swinging closures, and the object of the invention is the provision of a lock embodying a novel construction whereby the same may be readily inserted 15 within a circular opening bored in an edge of the door without the necessity of mortising the door in the usual manner.

The invention further contemplates a 20 novel means for mounting and operating the locking bolt whereby the latch actuating mechanism may be held against movement when it is desired to lock the door.

For a full understanding of the invention and the merits thereof and also to acquire a 25 knowledge of the details of construction and the means for effecting the result, reference is to be had to the following description and accompanying drawings, in which:

Figure 1 is a side elevation of a portion of 30 a door having the latch mounted thereon, the door being broken away and the cover for the latch casing being removed. Fig. 2 is a horizontal sectional view on the line 2-2 of Fig. 1. Fig. 3 is a plan view of the 35 latch mechanism, the latch proper being removed and the locking bolt being thrown into operative position. Fig. 4 is a transverse sectional view on the line 4-4 of Fig. 2. Fig. 5 is a transverse sectional view showing the key as inserted within the casing 40 previous to turning the same for throwing the locking bolt. Fig. 6 is a detail view of the latch, parts being separated. Fig. 7 is a detail view of the key.

45 Corresponding and like parts are referred to in the following description and indicated in all the views of the drawings by the same reference characters.

Referring to the drawings, the numeral 1 50 designates the casing within which the latch mechanism is mounted, the said casing being formed with an open side which is normally closed by the cover 1^a. Particular attention is directed to the fact that this casing 1 is circular in cross section, such a construction 55 having the advantage of enabling the casing

to be inserted within a circular opening bored in the edge of the door by any suitable means such as a brace bit. The outer end of the casing is provided with a plate 2 which is 60 designed to fit against the edge of the door and to be secured thereto by screws or other suitable fastening means. A hub 3 is mounted within the casing 1 at an intermediate point in the length thereof, the said 65 hub being formed upon its opposite sides with the usual bosses 3^a received within corresponding openings in the back of the casing and the cover 1^a. The rear portion of the hub 3 is flattened at 4 for coöperation 70 with the locking bolt 5, while the forward portion of the hub is provided upon one face with the outwardly projecting shoulders 6. For the purpose of turning the hub the usual 75 spindle 7 is utilized which has an angular section and passes through a square opening in the hub, knobs 8 of any suitable construction being applied to the extremities of the spindle which projects beyond opposite sides of the door. It will also be observed that 80 this spindle 7 passes through plates 9 secured to the sides of the door.

The latch bolt 10 is slidably mounted within the forward portion of the casing and has the rear end thereof bifurcated, the arms 85 10^a of the bifurcation being provided at their extremities with the laterally projecting lugs 11 which engage the respective shoulders 6 upon the hub. It will thus be obvious that by grasping one of the knobs 8 90 and turning the spindle 7 the hub 3 will be rotated in such a manner as to draw the latch bolt inwardly. The latch 12 slides freely through an opening in the end of the casing and is provided with a rearwardly extending 95 ear 13 by means of which it is detachably secured to the extremity of the latch bolt 10, such a construction admitting of the reversing of the latch so that the device can be employed either in connection with a 100 right or a left hand door. For the purpose of holding the latch 12 normally in an operative position a spring 14 is utilized which surrounds the latch bolt 10 and is interposed between the latch 12 and a shoulder 15 formed 105 by contracting an intermediate portion of the casing. In the present instance this spring has an approximately conical formation, the forward end thereof being tapered and received between rearward extensions 16 at the 110 top and bottom of the latch 12.

The locking bolt 5 is slidably mounted

upon the bottom of the casing 1 at the rear end thereof and is adapted to be moved into contact with the flattened portion 4 of the hub 3 so as to lock the latter member against 5 rotation. Projecting upwardly from the locking bolt 5 is a pin 17 designed to be received within either one of a pair of openings 18 in a locking plate 19 which bears 10 yieldingly against the upper side of the bolt and has a limited amount of vertical movement between the rear end of the casing and a rib 20 projecting downwardly from the top of the casing. A spring 21 interposed between the top of the casing and the locking 15 plate tends to force the latter member downwardly against the locking bolt and when the pin 17 is received within the forward opening 18 the locking bolt is held in operative position against the flattened portion 4 of the hub 3, while when the pin is 20 received within the rear opening 18 the locking bolt is held in an inoperative position and the latch 12 may be withdrawn in the usual manner by grasping one of the knobs 25 8 and turning the spindle. A notched or cut away portion 22 is formed in the lower portion of the locking bolt 5 for the reception of a key 23 designed to be inserted through the usual key hole openings 24 in 30 the front and rear of the casing, the plates 9 fitted to the sides of the door being also shown in the present instance as provided with openings for the reception of the key. Opposite ends of the notch 22 are enlarged 35 at 22^a to form a clearance space for the two bits 23^a upon the key, and these enlarged portions 22^a of the notch extend upwardly to the top of the locking bolt so that the bits of the key may come in contact with the 40 locking plate 19. Should the locking bolt be in an inoperative position when the key is inserted through the key-holes 24 and within the notch 22, when the key is turned the bits 23^a thereof will move freely within 45 the clearance spaces formed by the enlarged ends 22^a of the notches until they come into contact with the locking plate 19. A continued movement of the key after contact with the locking plate will lift the latter 50 against the action of the spring 21 until the pin 17 has been withdrawn from the opening 18, and will then engage the locking bolt to move the same forwardly against the flattened portion 4 of the hub. The pin 17 of 55 the locking bolt will then be in registry with the forward opening 18 and the spring 21 will force the locking plate 19 again into contact with the bolt. The hub 3 is then securely held against rotation and the latch 60 12 thereby locked in an operative position. In releasing the hub 3 the key is inserted within the latch and turned in the opposite direction, the bits 23^a thereof serving in an identical manner to first lift the locking 65 plate 19 out of engagement with the pin 17

and then move the locking bolt rearwardly until the said pin 17 enters the rear opening 18. As shown on the drawing the key 23 is preferably formed in two sections which are hinged to each other so as to be folded and 70 readily carried in the pocket, although such is not necessary for the purposes of the invention.

— For coöperation with the latch 12 a latch plate 25 is secured to the door casing and is 75 formed with a socket 26 to receive the latch and a beveled lip 27 for coöperation with the beveled face of the latch to force the same within the casing when the door is closed.

Having thus described the invention, what is claimed as new is:

1. In a latch, the combination of a latch bolt, a hub for operating the latch bolt, a 85 slideable locking bolt adapted to engage the hub to prevent the rotation thereof, and a locking plate having an interlocking connection with the locking bolt for holding the same either in an operative or an inoperative position.

2. In a latch, the combination of a latch bolt, a hub for operating the latch bolt, a locking bolt for engagement with the hub to prevent rotation thereof, a pin projecting from the locking bolt, and a locking plate 95 formed with openings designed to receive the pin to hold the locking bolt either in an operative or an inoperative position.

3. In a latch, the combination of a latch bolt, a hub for operating the latch bolt, a 100 slideable locking bolt adapted to engage the hub to prevent rotation thereof and formed with a recess to receive a key, a locking plate yieldingly engaging the locking bolt and having an interlocking connection there- 105 with to hold the same either in an operative or an inoperative position, and a key adapted to be received within the recessed portion of the locking bolt for releasing the locking plate from engagement there- 110 with and moving the locking bolt.

4. In a latch, the combination of a latch bolt, a hub for operating the latch bolt, a slideable locking bolt adapted to engage the hub to prevent rotation thereof and formed 115 with a recess to receive a key, a pin projecting from the locking bolt, a locking plate yieldingly engaging the locking bolt and formed with openings designed to receive the pin to hold the bolt either in an operative or inoperative position, and a key adapted to be received within the recessed portion of the locking bolt for moving the locking plate out of engagement with the pin and throwing the locking bolt.

5. In a latch, the combination of a latch bolt, a hub for operating the latch bolt, a 120 slideably mounted locking bolt adapted to engage the hub to prevent rotation thereof, the said locking bolt being formed with a 125

recess to receive a key and the ends of the recess being enlarged and extended to one side of the locking bolt, a pin projecting from the said side of the locking bolt, a locking plate yieldingly engaging the locking bolt and formed with openings designed to receive the pin to hold the locking bolt either in an operative or inoperative position, and a key adapted to be received within 10 the recessed portion of the locking bolt and

formed with bits adapted to operate within the enlarged ends thereof to move the locking plate out of engagement with the pin and throw the locking bolt.

In testimony whereof I affix my signature 15 in presence of two witnesses.
